SMOKE-REMOVER FOR ORDNANCE.

932,032.

Specification of Letters Patent. Patented Aug. 24, 1909.

Application filed May 12, 1903. Serial No. 432,534.

To all whom it may concern:

Be it known that we, JOHANNES KRONE, residing at Essen-on-the-Ruhr, and JULIUS BECKER, residing at Essen-on-the-Ruhr, Germany, both subjects of the Emperor of Germany, have invented a certain new and useful Improvement in Smoke - Removers for Ordnance, of which the following is a specification.

10 This invention relates to that type of apparatus for removing powder gases from gun barrels, in which a suction pipe is attached to the breech end of the gun barrel. Hitherto this kind of apparatus, which is 15 described for example in the specification of Patent No. 864152, has only been used on guns in which the breech opening passes through the outer surface of the breech end of the gun barrel, as is the case in wedge 20 breech mechanisms for example.

Now the object of the present invention is to provide an apparatus of the type above mentioned, which shall be capable of being used for that type of gun, in which the 25 breech opening is situated at the front of the breech end of the gun barrel, as is the case in screw and cam breech mechanisms for example.

In the drawing: Figure 1 shows a side view of a constructional form of the apparatus constituting the subject matter of the invention, together with those parts of a barrel recoil gun and gun platform with which the invention is connected. Furthermore, 35 and on a larger scale Fig. 2 is a section on the line 2—2 of Fig. 1, seen from the right. Fig. 3 is a section on the line 3—3 of Fig. 2, seen from the left, Fig. 4 is a side view, corresponding to Fig. 3, of the breech end of 40 the gun barrel. Fig. 5 is a section on the line 5—5 of Fig. 3, seen from above, and Fig. 6 is a section on the line 6—6 of Fig. 2, seen from the left.

The gun barrel A of the barrel recoil 45 gun—which is mounted in an armored turret—is movably mounted in the cradle C in the usual way, which latter is pivotally mounted, by means of the trunnions c', in the gun carriage D.

50 Alongside the gun carriage D is placed a fan E, to drive which an electric motor F is employed. To the fan E is attached a suction pipe E' and a delivery pipe E''. The said delivery pipe E'' leads through the roof

of the armored turret B and out into the 55 open air.

The gun barrel A has a cam breech mechanism G, G', the breech door G' of which is bounded on the side farthest from its pivot pin g² by a cylindrical face g³ curved to the 60 arc of a circle (see particularly Fig. 2), and the axis of which, when the breech mechanism is closed, coincides approximately with the longitudinal axis of the gun barrel.

To the breech end a' of the gun barrel is 65 attached, on the side lying farthest from the pivot pin g² of the breech door, a cap-shaped smoke trap a², which partially covers over the front and partially also the outer surface of the breech end a' in the manner shown in 70 the drawing (see particularly Figs. 2 and 5).

In the part of the smoke trap a² which covers over the front of the breech end, is provided a recess a³ (see Fig. 2) for the part 75 of the breech door G' bounded by the surface g³, the shape of the said recess corresponding to that of the surface g³.

The part of the smoke trap a² bounded by the recess a³ has an opening a⁴ (see Figs. 5 and 6), which lies opposite the surface g³ of 80 the breech door when the latter is closed. The opening a⁴ forms the inlet opening for the powder gases to be removed. In the side boundary wall of the part of the smoke trap a² which covers over the outer surface of the 85 breech end, is a rectangularly shaped opening a⁵, which forms the outlet opening for the powder gases. The part of the wall of the smoke trap a² containing the opening a⁵, 90 is provided with a flange a⁶, which is of rectangular form exactly like the opening a⁵, and the front of which forms a vertical plane to the axis of the trunnions c'.

The suction pipe E' is widened into box-shape at its free end, and provided with a 95 front wall e³ having a rectangular opening e⁴, and the outer boundary face of which forms a vertical plane at right angles to the axis of the trunnions c'. The arrangement is so contrived, that the wall e³ stands opposite and quite a small distance away from the flange a⁶ of the smoke trap a², when the gun barrel, as shown in the drawing, is in the loading position. The openings e⁴ of the 100 suction pipe E' and a⁵ of the smoke trap a² then lie directly opposite each other.

The opening e⁴ is of the same breadth as the opening a⁵, its height however is smaller

than the height of the opening α^5 . In consequence hereof, the powder gases to be removed can pass over out of the smoke trap α^2 into the suction pipe E' at any desired elevation of the gun barrel, and within certain limits dependent upon the differences of height of the openings e^4 and α^5 . Any elevation of the gun barrel lying between the above mentioned limits, can be regarded as 10 the loading position.

While shooting is going on, the fan E is continually in operation. After the gun has been fired with the barrel thereof elevated to correspond to the distance away of the target, the barrel recoils and then returns to the firing position again. At this stage the gun barrel is brought into the loading position, in which the opening α^5 of the smoke trap α^2 stands opposite the opening e^4 of the suction 20 pipe. If now the breech mechanism G, G' be opened, by swinging the breech door aside about the axis of the pin g^2 , after previously unlocking the breech piece G, the powder gases remaining behind in the gun barrel 25 will be drawn into the opening α^5 of the smoke trap, pass through the same, and proceed by the path α^5, e^4 into the suction pipe E' of the fan E, which forces them into the delivery pipe E'; from the delivery pipe E' 30 the powder gases pass above the roof of the armored turret, into the open air, where they are no longer able to trouble the crew of the gun.

Having thus described the invention, what 35 is claimed and desired to be secured by Letters Patent is:

1. In a smoke-remover for ordnance, the combination with a gun having an end opening breech closure; of a smoke collector 40 overlapping a portion of the end surface of the gun barrel, said collector being provided with an intake adjacent to the end opening in the breech; and means for creating suction in said smoke collector.

45 2. The combination with a gun provided with an end opening breech closure; of a smoke collector overlapping a portion of the end surface of the gun barrel, said collector being provided with an intake opening adjacent to the end opening of said barrel and constructed to partially encircle said breech opening.

50 3. The combination with a gun having an end opening breech closure, of a smoke collector overlapping a portion of the end surface of the gun barrel and also a portion of the jacket surface thereof and provided with an intake adjacent to the end opening of the gun breech and provided with an outlet 55 opening for said powder gases in that por-

tion which overlaps the jacket surface of the gun barrel, and means for causing a suction through said smoke collector.

4. The combination with a gun having an end opening breech closure, of a smoke collector overlapping a portion of the end surface of the gun barrel and provided with an intake adjacent to the end opening of the breech and with an outlet opening; and a suction conduit in close proximity to the smoke collector, said conduit having an intake in close proximity to the outlet opening of the smoke collector, and means for causing a suction through said suction conduit.

75 5. The combination with a gun having an end opening breech closure; of the hinge by which the breech closure is supported; a smoke collector overlapping a portion of the end surface of the gun barrel and surrounding that end of the hinge remote from its pintle, said collector being provided with an intake adjacent to the end opening of the breech; and means for inducing suction in the smoke collector.

80 6. The combination with a gun having an end opening breech closure; of the breech closure hinge provided with a cylindrical end remote from its pintle; a smoke collector having an open end conforming to the cylindrical end of the hinge said open end of the collector being arranged adjacent to the end opening of the breech; and means for inducing a suction in said smoke collector.

85 7. In an apparatus of the character described, the combination of the end opening breech block, the hinge supporting the same, said hinge being provided with a cylindrical end remote from its pintle, the smoke collector overlapping a portion of the end surface and jacket surface of the gun barrel, and provided with an open end in close conformation to the cylindrical end of the hinge when the breech is closed, said opening being arranged adjacent to the end opening of the breech; and an outlet in the outer wall of that portion of said collector which overlaps the jacket surface; a suction conduit having an opening adjacent to said outlet of the smoke collector, and means for inducing a suction in the suction conduit.

100 The foregoing specification signed at Dusseldorf, Germany, this 4th day of April, 1908.

JOHANNES KRONE.
JULIUS BECKER.
